Primary Examiner — Keith J Wilson

CLAIM

The ornamental design for an aerator, as shown and described.

DESCRIPTION

FIG. 1 is a perspective top view of the aerator;

FIG. 2 is a side view of the aerator;

FIG. 3 is a side perspective view of the aerator in which the portions of the aerator shown in broken lines form no part of the claimed design;

FIG. 4 is a perspective top view of the aerator; and,

FIG. 5 is a perspective top view of the aerator in which the portions of the aerator shown in broken lines form no part of the claimed design.

1 Claim, 5 Drawing Sheets
